DES. 2155

Nicholas S. Fedder, of Troy, N. Y.

Assignor to

Geo. Busch and Co. of Troy, N. Y.

Letters Patent No. 2155 Dated Aug. 11, 1863.

Design for a Stove Base.

The schedule referred to in these Letters Patent and making part of the same.

To all whom it may concern:

Be it known that I, Nicholas S. Fedder, of the City of Troy, in the County of Rensselaer, and State of New York, have invented or produced a new and original Design for a Stove Base, of which the following is a full, clear and exact description, reference being had to the accompanying photograph of a base of a stove embodying my said design.

This design for a stove base is distinguished from all others by having a continuous series of upward and inward-pointing tooth-like ornaments τ , along a moulded border on a bottom plate I ; an outer rosette σ moulding; an inner ornamented moulding κ , and a central ornament λ , on panels of the middle, upright-plate or plates M ; and a series of upward and inward-pointing, tooth-like ornaments σ , around the raised, annular, convex upper part of an ornamental top-plate O ; all shaped and arranged so as to present an appearance like that represented by the aforesaid photograph.

What I claim as my invention or production and desire to secure by Letters Patent is the design of the plates I , M and O , of a stove-base, as herein set forth.

Witnesses.

Eliakim Morse.

Nicholas S. Fedder.
